UNITED STATES PATENT OFFICE.

WILLIAM R. PASSANO, OF BALTIMORE, MARYLAND.

DESIGN FOR A PRESERVING-JAR.

No. 39,897.

Specification for Design.

Patented March 30, 1909.

Application filed January 9, 1909. Serial No. 471,537. Term of patent 14 years.

To all whom it may concern:

Be it known that I, WILLIAM R. PASSANO, a citizen of the United States, residing at Baltimore, in the State of Maryland, have invented a new, original, and ornamental Design for Preserving-Jars, of which the following is a specification, reference being had to the accompanying drawing, forming part thereof.

The figure is a perspective view of a jar, showing my new design.

I claim:

The ornamental design for a preserving jar, as shown.

WILLIAM R. PASSANO.

Witnesses:

CHAPIN A. FERGUSON,
WILLIAM WATKINS.
